DISPENSER FOR RAZOR BLADE CARTRIDGES

Martin Glaberson, Ardsley, N.Y., assignor to Warner-Lambert Company, Morris Plains, N.J.

Filed Oct. 22, 1971, Ser. No. 191,959

Term of patent 14 years

Int. Cl. D9—03

U.S. Cl. D9—189

FIG. 1 is a perspective view of a dispenser for razor blade cartridges showing my new design;

FIG. 2 is a plan view of the underside thereof;

FIG. 3 is a side elevation view thereof; and

FIG. 4 is a cross-sectional view thereof taken along line 4—4 of FIG. 2.

I claim:

The ornamental design for a dispenser for razor blade cartridges, as shown.
